UNITED STATES PATENT OFFICE

131,658

DESIGN FOR A PORTABLE POWER DRIVEN SCREW DRIVER UNIT

Alonzo G. Decker, Baltimore County, Md., assignor to The Black and Decker Manufacturing Company, a corporation of Maryland

Application July 17, 1941, Serial No. 102,198

Term of patent 7 years

To all whom it may concern:

Be it known that I, Alonzo G. Decker, a citizen of the United States and a resident of Baltimore County, State of Maryland, have invented a new, original, and ornamental Design for a Portable Power Driven Screw Driver Unit, of which the following is a specification, reference being had to the accompanying drawing, forming part thereof.

In the drawing:

Fig. 1 is a side elevational view of the portable power driven screw driver unit.

Fig. 2 is a front elevational view of the same, and

Fig. 3 is a top plan view thereof.

I claim:

The ornamental design for a portable power driven screw driver unit, substantially as shown.

ALONZO G. DECKER.
